UNITED STATES PATENT OFFICE.

JOSEPH H. FREEMAN, OF SHICKSHINNY, PENNSYLVANIA.

HORSESHOE CALK.

Application filed March 29, 1922. Serial No. 547,796.

To all whom it may concern:

Be it known that I, JOSEPH H. FREEMAN, a citizen of the United States, residing at Shickshinny, in the county of Luzerne and 5 State of Pennsylvania, have invented a new and useful Horseshoe Calk, of which the following is a specification.

This invention relates to horseshoe calks and particularly to detachable calks.

10 The object is to provide a calk to be used in connection with a horseshoe having certain means incorporated therein, whereby the said calk may be readily attached to the shoe by merely driving the same into position, the calk and the shoe having coacting parts which effectually prevent the accidental dislodgment of the calk from its seat while in use, but permit of the removal of the same from the shoe when the calk has 15 become worn and requires renewal.

Another object is to provide a detachable horseshoe calk which may be easily formed by forging the same singly or in pairs for attachment to the toe of the shoe; 20 the heel of the shoe, of course, receiving single calks, the said calks having expandable and contractible tenons for automatically interlocking into peculiarly formed sockets located at the toe and the heel of said 25 shoe, and having beveled or tapering recesses at each side for the reception of the spaced prongs of a special tool, by means of which the single calk or the double or twin form of calk may be pried from its seat in the 30 shoe.

A full and complete understanding of the invention may be obtained from a consideration of the following detailed description, taken in connection with the accompanying drawing forming a part of this 35 specification; it being understood that while the drawing shows a practical form of the invention, the latter is not confined to strict conformity with the showing thereof, but 40 may be changed or modified, so long as such changes or modifications mark no material departure from the salient features of the invention, as specifically pointed out in the appended claims.

45 In the drawing, in which similar reference characters designate corresponding parts throughout the several figures:—

50 Figure 1 is an inverted plan view of a horseshoe provided with the improved calks;

Fig. 2 is a sectional view of the shoe in the position assumed while in use;

Fig. 3 is a transverse sectional view through the toe of the shoe and showing a pair of spaced toe calks in position therein; 60

Fig. 4 is a detail perspective view of a single calk applicable for use at the toe or the heel of the shoe and formed with a relatively sharp edge for use in slippery weather; 65

Fig. 5 is a similar view of a calk constructed for use in dry weather;

Fig. 6 is a face view of a double or twin form of calk;

Fig. 7 is a detail elevation of one of the heel portions of the shoe and showing the method of applying a special tool for removing the calk; and

Fig. 8 is a perspective view of the special tool for detaching the calks. 75

The horseshoe 1, as illustrated in Fig. 1 of the drawing, may assume any of the shapes in common use, and is preferably provided in each branch or arm of the same with a thickened portion 2 adjacent to the heel ends and on the under side of the shoe, and in like manner the front or toe of the shoe is provided with a centrally disposed enlargement 3 extending downwardly from the under face of the same, the shoe being 85 straight and flat on its upper face.

The front or toe enlargement 3 extends transversely of the central portion of the shoe and is provided with a pair of spaced sockets 4 arranged side by side and extending through the shoe, and in like manner the rear terminal of each branch or arm is equipped with a heel socket 4 formed, in every respect, the same as the toe sockets except that the general inclinations of the 95 sockets are reversed, the toe sockets having their longitudinal axes slanting downwardly towards the front while the axes of the heel sockets slant towards the rear.

Each socket is rectangular in cross-section, preferably square, though these dimensions may differ, and the walls of the sockets converge upwardly towards the upper face of the shoe so as to form a wedge-shaped seat for the interfitting and locking 100 portions of the calks, as will be described.

At the upper end, each socket is provided, in its longitudinally disposed walls, with opposed outwardly and upwardly flaring walls 5 into which are adapted to be seated 110

certain portions of the calks for locking the same into position on the shoe, and the parts, as thus far described, constitute all of the features necessary to be incorporated 5 into the shoe proper.

Adapted to be seated into any one of the sockets 4 formed at the toe or the heel of the shoe is a calk 6, which may be readily formed by a simple process of forging to comprise 10 a base portion 7 preferably flat across its front face and having its rear edge 8 rounded, as clearly shown in Fig. 4. The base portion is provided with an extension 9, for engagement with the ground, and the said 15 extension may be of the form shown in Fig. 4, wherein the rear side of the extension is concave, as at 10, to provide a relatively sharp contacting surface or edge at its lower end, to be used in wet or slippery weather; 20 or the said extension may be as wide as the base portion 7, as indicated at 9^a in Fig. 5, the latter form constituting a blunt calk for use in dry weather.

In either form of the calk, the upper end 25 of the body portion 7 is equipped with a normally upstanding tenon 11, rectangular in cross-section, and having its four sides tapering towards the top, in accordance with the walls of the sockets 4, into which the same is 30 adapted to be fitted.

The tenons 11 are arranged, with relation 35 to the base portion 7, with one of their walls substantially coextensive with one wall of the same, thus providing at the opposite side a shoulder 12 which, when the tenon of the calk is fitted in the socket 4, is adapted to bear on the lower face of either the enlargement 2, at the heel of the shoe, or the enlargement 3 at the toe thereof, as clearly shown 40 in Fig. 2.

The upper end of the tenon is provided on its longitudinal sides with outwardly projecting inclined walls 13, extending from the front to the rear thereof and adapted, when 45 the tenon is fitted into one of the sockets 4, to snugly fit the inclined walls 5 thereof, with the upper end of the tenon flush with the upper face of the shoe 1. In order to permit of this seating of the enlarged end of the 50 tenon into the seat formed by the walls 5, the tenon is further provided at its upper end with a bifurcation 14, preferably tapered or V-shaped, extending substantially half the length of said tenon and providing legs capable of being flexed or forced toward each 55 other when driven with sufficient force into the socket, and allowing the enlargements 13 of the tenon to gradually bend toward each other, while under pressure, and to spring 60 or snap outwardly into the seat provided by the tapered walls 5 of the socket, as clearly shown in Fig. 3.

The upper face of the base portion 7 of the calk at either side of the tenon is oppositely inclined, as indicated at 15, so that

when the calk is driven into its seat in the socket, a tapered or wedge-shaped recess is provided at each side of the calk for the introduction of the spaced tapering prongs 16 of a tool 17 to be used in detaching the calks 70 from the shoes, as illustrated in Fig. 7. This tool, illustrated in Fig. 8, may consist, as stated, in the spaced prongs 16 which may be formed integrally with and project laterally from the shank of the tool, the same 75 being extended to one side to form a convenient handle 18. In applying the tool, it is only necessary to introduce the tapered ends of the prongs into the tapered recesses formed between the inclined walls 15 of the calk and the lower side of the shoe, with one of the prongs at either side, and this may be done either from the front or the rear of said calk. By hammering on the shank 17 of the tool at a point in a line with the calk, it will 80 be seen that the tapered ends of the prongs will force the calk longitudinally from its seat, the upper ends of the tenon at either side of the bifurcation 14, being forced to approach each other, through the action of 85 the inclined walls 13 on the corresponding walls 5 of the socket, until the narrow or contracted point of the socket is reached, when the calk may be readily removed from the shoe. 90

By reason of the opposite inclination of the axles of the front and rear sockets, the calks, fitted into the same, are correspondingly inclined; that is, the toe calks are directed forwardly and the heel calks rearwardly, to provide a more solid bearing for 100 the shoe upon the ground.

The toe calks, as stated, may consist of two single calks, or the same may be formed on a single base 7^a, as indicated in Fig. 6, the tenons in this form being exactly the same as heretofore described and arranged in spaced relation on the said base 7^a to be properly fitted into the spaced sockets 4 at the toe portion of the shoe. 110

The heel and toe calks are reversely arranged, as shown in Figs. 1 and 2, so that the bearing edge of the extension 9 is in advance at the toe of the shoe, while those at the heel of the shoe are in the rear thereof. 115

From the foregoing, it will be seen that a simple, strong, and durable calk for use at the toe or heel of a horseshoe has been provided, and that the necessary features for receiving and holding said calk in the shoe may be easily formed during the process of manufacturing said shoe, the enlargements thereon having the sockets, being readily produced by a simple forging process, and that the calks themselves may be similarly formed, thus greatly reducing the 120 cost of production.

What is claimed is:—

1. The combination with a metallic shoe 125 provided with a rectangular socket having

two opposite walls converging throughout their length from the bottom to the top, and the other two walls converging from the bottom for a major portion of their length 5 and terminating at the top in outwardly-flared seats, of a calk comprising a body member adapted to bear against the lower face of the shoe and having an upwardly-tapering tenon of resilient material extending therefrom and fitting the socket, said tenon having at its upper end a transverse V-shaped cleft between the flared seats of the socket to permit the insertion or removal thereof.

15 2. The combination with a horseshoe having sockets formed in the heel and toe portions thereof, each socket being rectangular in cross-section and having its walls converging towards the top and there terminating on its transversely opposite sides in outwardly-flared walls to constitute seats, of a plurality of calks, each comprising a body member adapted to bear against the lower face of the shoe and having a ground-engaging 20 portion, an upstanding tenon formed on the body member and having tapering sides to fit the socket in the shoe, said tenon being arranged to one side of the center of the base and having a central V-shaped cleft at 25 its upper end to provide resilient terminal arms, extensions formed on the outer upper edges of the arms and having their lower faces beveled and parallel to the cleft to be compressed when driven into the socket of

the shoe and to spring outwardly and into 09 the seats at the upper end of the socket to retain the calk in position.

3. The combination with a horseshoe having sockets formed in the heel and toe thereof, the longitudinal axis of each socket being arranged at a slight angle to the upper face of the shoe, each socket being square in cross-section and having its walls tapering towards the upper face of the shoe and extending through the same, the longitudinal walls terminating on opposite transverse sides in upper outwardly-flared beveled seats, of a plurality of calks, each having a body member provided with a depending ground-engaging portion, an upstanding tenon formed integrally therewith and having its upper end bifurcated longitudinally of the shoe and provided with outwardly-extending enlargements to fit said seats, said tenon being arranged with one wall flush with one side edge of the base to provide around three sides a shoulder adapted to bear against the lower side of the shoe, the two oppositely-disposed side portions of the shoulder being inclined forwardly and rearwardly from the center to provide tapering recesses for the introduction of a wedge-shaped tool for forcing the tenon from the socket.

In testimony that I claim the foregoing 65 as my own, I have hereto affixed my signature.

JOSEPH H. FREEMAN.
